GRASS CATCHER FOR A LAWN MOWER

Raymond K. Strasel, Winthrop Harbor, Ill., and
John W. Barth, Cudahy, Wis.

Application May 9, 1958, Serial No. 50,812

Term of patent 14 years

(Cl. D40—1).

Fig. 2

Fig. 3

Fig. 4

Fig. 1

Fig. 1 is a front perspective view of a grass catcher for a lawn mower showing our new design.

Fig. 2 is a top plan-view of the catcher shown in Fig. 1.

Fig. 3 is a side elevational view of the catcher shown in Fig. 1, but showing the side opposite to that shown in Fig. 1.

Fig. 4 is a rear elevational view of the catcher shown in Fig. 1.

We claim:

The ornamental design for a grass catcher for a lawn mover, substantially as shown.
